UNITED STATES PATENT OFFICE.

PETER COOPER HEWITT, OF RINGWOOD MANOR, NEW JERSEY; THE FARMERS' LOAN AND TRUST COMPANY, EXECUTOR OF SAID PETER COOPER HEWITT, DECEASED, AS SIGNOR TO COOPER HEWITT ELECTRIC COMPANY, OF HOBOKEN, NEW JERSEY, A CORPORATION OF NEW JERSEY.

ELECTRIC APPARATUS.

Application filed July 30, 1920. Serial No. 400,292.

The object of this invention is to provide very sensitive means for receiving minute electrical variations and consists in the control of the reactions affecting the conducting condition of the space between two electrodes in an evacuated vessel.

My invention consists of an evacuated vessel exhausted to a vacuum sufficiently high to obtain the results desired and in case of their use for receiving wireless messages when exhausted to a high vacuum a difference of potential may be applied between the positive terminal and the filament acting as the negative of the work circuit or output circuit. Apparently, the higher this potential difference is made, the greater the variation will be in the output circuit, for the same signal. In other words, the greater the difference of potential between the positive terminal of the receiving circuit and the negative, the greater the sensitiveness of the device, within comparatively wide limits, and under certain conditions, although low resistance devices of this principle are very sensitive. The size of the positive terminal and its surface area bear a direct relation to this difference of potential and the larger the positive the lower its resistance other things being equal. The size of the filament, which is the negative electrode terminal and its area affect this difference of potential as well as the temperature at which its is operated.

By making the positive large and the filament small, a larger proportion of the resistance to the passage of the current can be had at the negative terminal.

By making the positive relatively small as to its surface and size and the negative filament relatively large, the larger proportion of resistance may be had at the positive terminal. These relations are important for specific uses, as they enable the control of the reactions or resistance phenomena occurring at or about either the positive or the negative terminal and the reaction at either may be so made available for use when in close proximity to the effect of a charge acting on the device. This enables the use of the specific characteristics of each occurring within the device.

These reactions are sensitive in varying

degrees to potential variations affecting them and such potential variations may be caused to affect the reactions by an independent charged conductor or conductors properly located within the device and the charge may be made definite in direction by a potential difference applied between one conductor and another. The conductor or conductors used for applying a charge may be called potential terminal or terminals and have for their function the creation of a state of electrical stress in a definite direction and location within the device. By means of such stress, reactions occurring in the path between the positive and the negative terminals of the work circuit, the action of the device may be modified and controlled.

The reactions manifest at or in close proximity to the positive terminal and at or in close proximity to the negative terminal, and the reactions that may reside between these two sets of reactions, may be affected in such manner by electrical stress that some of them may manifest equal and opposite resistance characteristics, so that although there has been a wide change of the resistance distribution within the device, there will be but slight change of resistance in the circuit of the device. The purpose of applying charges in a definite direction and definite localities and by properly correlating the size of the negative and positive terminals, is to prevent the annulling of one resistance change by another by modifying the magnitude of one of these reactions by means of the relative size of the electrodes, the direction of the charge applied, and the degree

of vacuum within the device. These reactions may be so correlated that their tendency is to increase together or decrease together and so by their annulment or by action developed the total resistance manifestation may approximate one resistance change or the sum of two or more in the same direction; that is, increase or decrease, so that the total change of resistance over the device may be made to approximate the sum of the resistance reactions within the device acting in the same way.

I provide a high resistance connection between the positive electrode of the output circuit and the circuit connected to one of

the potential terminals of the input circuit, causing the potential terminal to be acted on positively. The high resistance connection tends to correlate the internal charges of the various terminals each with relation to the other, the device will operate without the high resistance connection but is usually not so sensitive nor so stable as with this connection. In devices of this character, 10 terminals are apt or may receive charges from the interior of the device by reason of reactions developed in the device. The high resistance positive connection provides means for utilizing such charges and in a 15 certain measure determining and fixing the electrical relation of each with respect to the other thereby tending to produce uniformity of and the utilization of the internal relations in the device. The high resistance used to connect the potential terminal circuit to the output positive electrode is in 20 order of from 50,000,000 to 500,000,000 ohms.

I prefer to apply the incoming variations 25 by means of a circuit connecting the potential terminals and prefer that a portion of such circuit be so located that a difference of potential is obtained between two potential terminals within the device. This may 30 be done by tuning that particular circuit with reference to the frequency to be received and affecting it by the incoming signal or in case of lower frequency by causing a secondary of a transformer to give a difference of potential to the potential terminals.

My device is particularly applicable to 40 very high frequencies such as are used in wireless telegraphy and even higher frequencies and also to low frequencies such as would come within the range of musical notes and even lower frequencies.

In my device the main negative electrode 45 consists of tungsten wire of about .002 inches diameter and substantially five-eighth inches in length, and is heated to a temperature required for its operation as a negative. The negative electrode is connected by means of a circuit having a suitable 50 source of current of from twenty to two hundred volts or more to the positive electrode. The positive electrode is about .005 inches in diameter and about one inch long and of tungsten and is separated from the 55 negative electrode by about five thirty-seconds of an inch. The potential terminals are of tungsten and about .005 inches in diameter and one inch long and separated from each other by about one-eighth of an 60 inch, and under service conditions, have practically no electrical leak or power of transmitting current when acting as a negative, they are capable of producing in the space separating them a stress as if by nature the separation were of a dielectric so

far as they are concerned. In other words, the relation of the one terminal to the other is that as if they were separated by a dielectric rather than that of a conductor and by means the action on the conductivity of the 70 space and included reactions forming part of the output circuit may be considered to change in conductivity due to dielectric stress brought about by difference of potential at the potential terminals. 75

One of the objects of this invention is to provide a device that will be sensitive to electrical variations of a very minute order and be sensitive to variations small as compared with those capable of being received 80 by a sensitive crystal or electrolytic detector, and provide a device which in itself has the quality of inherent silence. In fact, so minute as to be incapable of detection by a sensitive telephone connected in the output circuit of a device, but the currents nevertheless in this circuit being passed through a suitable cascade of amplifiers and multiplied many thousand times make the minute 85 variations eventually recognizable in a 90 translating device.

I have found the advantageous selection 95 of material within the device is very important for suppressing internal physical or chemical action due to the presence of current; any such action is apt to manifest itself in variation in a uniform current passing through the device and may on magnification be perceived by the use of a telephone giving rise to a sense of crackling or hissing 100 noises.

I have illustrated my invention in the accompanying drawings, in which Figure 1 is a diagram of a radio receiving circuit in which my improved device is utilized as 105 a detector in conjunction with an amplifier cascade and translating devices; Figure 2 is a diagram showing an alternative connection for the cascade amplifiers; Figure 3 is a view of a tube having a positive electrode and potential terminals of straight wire and a coiled wire negative electrode, all the terminals and electrodes being parallel and substantially coextensive in the tube; Figure 4 is a section on the line 4—4 of Figure 3; Figure 5 is a view of a tube having all its 110 electrodes and terminals of coiled wire, said electrodes and terminals being parallel and substantially coextensive and extending horizontally across the tube; Figure 6 is a section on the line 6—6 of Figure 5; and Figure 7 is a diagram of a novel form of electrostatic coupling between a detector and its 115 antenna. 120

A specific form of evacuated device embodying my invention is had in the accompanying drawing and consists of an enclosing vessel 1 made of glass, having suitable leads sealed in through the walls of the vessel and connecting with the various terminals 125 130

within the device. A positive terminal 2 being a tungsten wire, a filament 3 connected therewith by means of circuit 4 which includes a battery 5 and an inductance 6. The 5 filament 3 has an energizing circuit 7 including resistance 8, battery 9, and circuit 7, for the purpose of maintaining it at the desired temperature. Potential terminals 10 and 11 are located either side of the current path 10 12 between the positive terminal 2 and the negative terminal 3 of the receiving circuit. These terminals 10 and 11 are connected in and by circuit 13 having included in it an inductance 14. This circuit is connected to 15 the positive electrode 2 by means of a high resistance 23, thereby causing the potential terminals to be acted on and form part of the circuit of the positive terminal 2. The inductance 14 is in inductive relation to the 20 inductance 15 by means of which the incoming applied energy to be received is applied, 14 and 15 forming the secondary and primary of a transformer and the circuit of 14 is preferably tuned in resonance to the time 25 period of the incoming signal. The applied energy creates variation of potential at the terminals 10 and 11 causing an electric stress between them and the conducting space 12 and bring about variations of the electrical 30 reactions in space 12 as well as at the surface of the terminals 2 and 3, whereby variations of resistance are brought about in circuit 4 causing a variation of current flow and a variation of energy derived from the battery 35 5 causing variation in the inductance 6 affecting the inductance 16, 6 and 16 being the primary and secondary of a transformer and 16 is included in a circuit 17 which is the output circuit and contains the translating 40 or receiving device 18 here shown as a telephone. 15 is shown as forming part of an aerial circuit and is the source of input variations. This circuit comprises variable condenser 19, aerial 20 and ground lead 21. 45 The ground lead 21 is connected by means of line 22 to the positive lead 2 of the circuit 4 and may be also connected to the lead from the potential terminal 10 through its circuit 13 by means of the high resistance 50 23, extending from circuit 13 to circuit 22, whereby the terminals of all the circuits are connected to ground.

Inductance 14 connecting the two potential terminals 10 and 11 is preferably in resonance with the time period of the signals to be received. Most sensitive operation may be obtained from this coil when it is spiral of fine wire or ribbon wound with paper or other small capacity insulator between the 55 convolutions, as shown at 16^a, Figure 7. Such a coil being in circuit with the device, by having its terminals connected to the potential terminals, is very sensitive to minute electrical charges or variations applied statically. Such variations may be applied 60

statically by the use of a coil of shorter time period than the time period of the variations desired to be received, by placing on its surface a small surface of conductor, shown at 25. When this conductor 25 is electrically connected to the source of electrical variation, the time period of the coil will be lengthened due to its added capacity. In such relation the time period of the coil and its circuit for the best operation should then 70 be the same or approximately the same as that of the variation to be received. The desired circuit and connection provide very sensitive means for receiving wireless signals or transmitting speech electrostatically. 75

I claim as my invention:

1. An electric device comprising a container, a negative electrode therein, a positive electrode cooperating with said negative, a potential terminal in operative relation to said electrodes, and a fifty megohm resistance connecting the positive terminal to the potential terminal peculiar to said terminals. 80
2. An electric device comprising a container, a negative electrode and a positive electrode therein and extending across the container in parallel relation, and a pair of control electrodes substantially coextensive with and parallel to said electrodes and out of the path between said electrodes, and a high resistance connection from the positive electrode to one of said control electrodes. 85
3. An electric device comprising a container, a negative electrode and a positive electrode therein in parallel relation, and a pair of potential terminals in parallel relation in a plane at an angle to the plane of said electrodes and substantially coextensive therewith, a resistance of more than ten megohms connecting the positive electrode and a potential terminal. 90
4. An electric device comprising a container, a negative electrode and a positive electrode therein in parallel relation, a pair of potential terminals in parallel relation and in a plane at an angle to the plane of said electrodes and substantially coextensive therewith, and a high resistance connection between the positive electrode and a potential terminal. 105
5. An exhausted container containing positive and negative electrodes and two potential terminals connected by a circuit, said circuit being connected to the positive electrode by means of a high resistance peculiar to said positive electrode. 110
6. An exhausted container containing positive and negative electrodes, and two potential terminals connected by a circuit having inductance of definite time period, said circuit being connected to the positive electrode by means of a high resistance peculiar to said positive electrode. 125
7. An exhausted container containing posi- 130

- tive and negative electrodes and two potential terminals connected by a circuit potential terminal connected by a circuit having included in it a spiral of definite time period, said circuit being connected to the positive electrode by means of a high resistance peculiar to the positive electrode.
8. An electric circuit and an electronic device connected thereto, the electronic device comprising an envelope and electrodes in said envelope and being characterized by the following relationship of said electrodes: a negative electrode of tungsten wire of about 0.002" diameter and substantially five-eighths of an inch in length, a positive electrode of tungsten wire of about 0.005" in diameter and about one inch in length, said negative and positive electrodes being spaced apart five-thirty-seconds of an inch, a pair of supplementary electrodes of tungsten of about 0.005" diameter and about one inch in length and separated from each other about one-eighth of an inch, a lead for each end of said negative electrode and a lead for each of the other of said electrodes.
9. An electric circuit and an electronic device connected thereto, the electronic device comprising an envelope and electrodes in said envelope and being characterized by the following relationship of said electrodes: a negative electrode of tungsten wire of about 0.002" diameter and substantially five-eighths of an inch in length, a positive electrode of tungsten wire of about 0.005" in diameter and about one inch in length, said negative and positive electrodes being spaced apart five-thirty-seconds of an inch, a pair of supplementary electrodes of tungsten of about 0.005" diameter and about one inch in length, separated from each other about one-eighth of an inch, and positioned one on each side of the path between the negative electrode and the positive electrode, all of said electrodes being mounted in parallel relation, a lead for each end of the negative electrode and a lead for each of the other of said electrodes, and a resistance of more than ten megohms

in a connection between positive electrode 45 and one of said supplementary electrodes.

10. An electronic device comprising an envelope and electrodes in said envelope, said device being characterized by the following relationship of said electrodes: a negative 50 electrode of tungsten wire of about 0.002" diameter and substantially five-eighths of an inch in length, a positive electrode of tungsten wire of about 0.005" in diameter and about one inch in length, said negative 55 and positive electrodes being spaced apart five-thirty-seconds of an inch, a pair of supplementary electrodes of tungsten of about 0.005" diameter and about one inch in length and separated from each other about 60 one-eighth of an inch, a lead for each end of said negative electrode and a lead for each of the other of said electrodes.

11. An electronic device comprising an envelope and electrodes in said envelope, said device being characterized by the following relationship of said electrodes: A negative electrode of tungsten wire of about 0.002" diameter and substantially five-eighths of an inch in length, a positive electrode of tungsten wire of about 0.005" in diameter and about one inch in length, said negative 70 and positive electrodes being spaced apart five-thirty-seconds of an inch, a pair of supplementary electrodes of tungsten of about 75 0.005" diameter and about one inch in length, separated from each other about one-eighth of an inch, and positioned one on each side of the path between the negative electrode and the positive electrode, all of 80 said electrodes being mounted in parallel relation, a lead for each end of the negative electrode and a lead for each of the other of said electrodes.

In testimony whereof I hereto affix my 85 signature.

PETER COOPER HEWITT.
